UNITED STATES PATENT OFFICE

AARON J. MERSHON, OF WARSAW, INDIANA.

ROCK-DRILL.

SPECIFICATION forming part of Letters Patent No. 251,723, dated January 3, 1882.

Application filed November 10, 1881. (No model.)

To all whom it may concern:

Be it known that I, AARON J. MERSHON, a citizen of the United States, residing at Warsaw, in the county of Kosciusko and State of Indiana, have invented certain new and useful Improvements in Rock-Drills; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to improvements in rock-drills to be operated by hand or other power, it being designed as an improvement on the one for which Letters Patent were issued to me on the 1st day of May, 1877, No. 190,232, the object of my present improvements being to provide new devices for raising the drill, and novel combinations thereof, whereby said drill may be operated more rapidly and effectively, as will be more fully described herein-after. I attain these objects by the mechanism illustrated in the accompanying drawings, in which—

Figure 1 is a perspective view, showing the parts of the machine in position for operation upon an adjustable frame. Fig. 2 is a plan view of a portion of the machine, showing a portion of the frame and of the axle, the balance-wheel, the lifting and depressing arms, the pivoted lever which aids in placing the lower arm in position, and a portion of the guide for the upper one; and Fig. 3 is a vertical elevation, partly in section, showing a portion of the driving-shaft, one of its bearings, the balance-wheel with one of its lifting sockets, the lifting and depressing arms, the rod for aiding in bringing the one which lifts the drill into position, and the drill-stock.

Similar letters refer to similar parts throughout the several views.

In constructing drills of this type having my improvements embodied therein I provide a suitable frame, A, which may be of iron or wood, it having brackets A' A' in its corners, through which pass screw-bolts A² A² for the purpose of adjusting said frame to its proper position, either on a level or at an angle.

To the frame, at proper points, there are attached brackets B B, (or a frame-work,) which carry upon their upper surface bearings for the shaft B' to rotate in, said brackets being so placed as to support the shaft as near to its ends as practicable. This shaft is provided upon one of its outer ends with a crank, B², for rotating it by hand, or it may be a pulley or gear-wheel, by which it may be driven by any convenient power. To the opposite end of shaft B' there is secured a balance-wheel, C, the outer face of which is provided with two or more cup-shaped projections, C' and C², which, when the wheel is rotated, lift the drill by coming in contact with an arm placed thereon, said projections being placed at such a distance from the center of the axle as to give the required lift to the drill, and they may, if preferred, be made adjustable on the wheel, and thus rendered capable of giving a greater or less lift thereto.

The shaft B' may be extended through the wheel C and have a crank upon its end, as shown in Fig. 2, so that when the drill is operated by hand two persons may be employed for that purpose at the same time.

To the end of the frame which is nearest the balance-wheel there is secured a post or column, D, which rises sufficiently high to cause it to support the drill-stock, it being provided upon its inner surface with projections D' and D², which are furnished with holes, through which the drill-stock E passes. Upon the stock E there are placed two arms, E' and E², the upper one projecting into a groove or recess formed in the inner face of the column D for its reception, and it has attached to its inner end a spiral spring, E³, the lower end of which is attached to the column or to the frame, in order that as the drill-stock, after being raised by the projections on the balance-wheel, is relieved from the control thereof, an impetus may be given to its downward movement by the action of said spring, the drill-stock and the drill being allowed to continue their downward movement after the spring has been fully retracted, owing to the fact that the stock passes loosely through the socket formed in the arm E².

The arm E' is used for raising the drill, it, like E², having a socket in one of its ends,

through which the stock passes freely, while its opposite end extends toward the balance-wheel sufficiently far to permit each of the projections thereon to come in contact with it, and so carry the drill stock up, in doing which the arm is caused to partially rotate upon the stock, it being thus released from the control of said projections. This leaves the arm out of the path of the succeeding projection, and the drill would cease to be operated but that provision is made for returning it to its proper place, which is accomplished in the manner now to be described.

To the frame A there is pivoted a lever, F, which extends upward, and is passed through an eyebolt secured in the arm E', or it may be through a projection formed thereon, and is continued upward therefrom to the required distance. This lever is so placed and formed that when the free end of the arm E' is out of the path of the approaching projection said projection comes in contact with the lever, and so turns the arm and brings it into the path of the projection in time to cause it to carry the drill-stock up with it.

The drill, which may be of any approved form and of any desired size, is placed in a socket upon the lower end of the stock, to which it may be secured in any approved manner.

For the purpose of giving additional force

to the drill, there is placed upon the outer end of the stock E a weight, E⁴, which is secured thereto by a set-screw, as shown in Fig. 1, so that it may be adjusted thereon or removed 35 when desired.

Having thus described my invention, what I claim, and desire to secure by Letters Patent, is—

1. The combination, in a rock-drill to be 40 driven by hand or other power, of a balance-wheel, C, having upon its face segmentally-formed lifting-projections, a lifting-arm for raising the drill, a drill-stock, said arm being placed loosely upon the drill-stock so as to 45 turn thereon, an arm for giving impetus to the downward movement of the drill, and a spring for aiding such movement, all substantially as described.

2. The combination of the adjustable frame 50 A, the column D, drill stock E, and spring E³, substantially as shown and described.

3. The combination of the pivoted lever F and the arm E', substantially as and for the purpose set forth.

In testimony whereof I affix my signature in presence of two witnesses.

AARON J. MERSHON.
